ATTRITION MILL

Dix B. McLaughlin, Winona, Minn.

Application January 24, 1929, Serial No. 334,759

9 Claims.

(Cl. 83—8)

It is common practice to mount the grinding heads of attrition mills upon the ends of a pair of axially aligned shafts and to feed the grain or other material to be ground through a central opening in one of the heads. In operation the rapidly rotating heads create suction in the feed passageway, the ground material being delivered at the outer periphery of the heads. Gravel, small pieces of rock and other objectionable foreign matter are frequently mixed with the grain to be ground and are sometimes delivered into the mill. It is important to exclude as much of this foreign matter as possible both for the protection of the grinding plates and to improve the product.

In my improved mill I increase the rate of grinding and make a more uniform product by providing means for properly distributing the grain in the feed passages and for automatically separating the heavier foreign matter from the grain in the mill.

Further, in order to save wear on the bearings and retain the proper parallelism of the grinding heads, it will be evident that the runners or shafts driving the grinding heads should be supported at points as closely adjacent to the grinding faces as possible. One of my objects is to provide an arrangement whereby the weight of the grinding heads is supported more closely adjacent to the grinding faces than has heretofore been possible.

My invention will be best understood by reference to the accompanying drawing in which Figure 1 is a side elevation of my improved attrition mill; Fig. 2 is a central longitudinal section through the mill proper; Fig. 3 is a transverse section taken on the line 3—3 of Fig. 1 and Fig. 4 is a detail front elevation of the feed pedestal and cone.

The several parts of the machine are secured to a suitable bed 4 and motors 5 and 6 are arranged to drive the head and tail shafts 7 and 8, respectively. These shafts 7 and 8 are mounted in axial alignment and are revoluble in a series of bearings supported in standards 9, 10 and 11 and in a fourth bearing, hereinafter particularly described. The ends of the shafts 7 and 8 extend in close proximity, one to the other, within a housing 12 between the motors 5 and 6 and within this housing grinding heads 13 and 14 are respectively mounted on said shafts. To support the overhanging end of the shaft 7 an anti-friction bearing 15 is placed in the hollow interior of a substantially conical projection or deflector 16 formed in a base 17 supporting a

hopper 18 for the material to be ground. The otherwise conical deflector 16 has a series of annular shoulders or rings 16a upon its surface to direct the material toward the grinding heads and around the deflector. A conduit 19 for conducting the material to be ground to the grinding heads extends around the exterior of the conical projection 16 and communicates with the working faces of the grinding plates 20 through openings 21 in the head 13. A hub 13a of the head 13 is fixed on the extremity of the shaft 7 and the material to be ground passes through the openings 21 between spokes 13b of the head. Beneath the conical projection 16 is a receptacle 22 for the heavier foreign matter and an opening 23 in the base 17 allows access to the receptacle 22 upon the removal of a plate 23a (Figs. 1 and 3). Air is admitted to the conduit 19 through a screen-covered opening 24 beneath the hopper 18. A suitable feed roll 25 is arranged to be driven by a belt (not shown) running on a drive pulley 26 on the shaft 7 and on a driven pulley 27 on the spindle of the roll 25.

To support the shaft 8 at a point closely adjacent to the grinding head 14, an anti-friction bearing 28 is mounted in the standard 10. Access to the bearings 15 and 28 is facilitated by providing removable plates 29 around the shafts 7 and 8 and enclosing the bearing recesses respectively.

Operation

The motors 5 and 6 are operated to drive the shafts 7 and 8 in opposite directions so that the grinding plates 20 are rotated at high speed in opposite directions. Grain or other material to be ground may be fed continuously from the hopper 18 by the operation of the feed roll 25. The rapidly rotating heads 13 and 14 cause the material to be directed outward by centrifugal force so that the material is delivered through an opening 30 in the bed 4 and suction is created in the feed conduit 19. Air is drawn in through the opening 24 and as it approaches the grinding head 13 it is given swirling or rotary motion about the conical surface of the member 16. The material to be ground is thus continuously delivered to the grinding surfaces and distributed uniformly to the several segments of the plates 20. The heavier particles of foreign matter drop from the hopper upon the deflector 16 and the spokes 13b assisted by the swirling draft of air direct such particles outward and backward into the receptacle 22 where they lodge beneath the conical surface. The receptacle 22 may be

periodically emptied through the opening 23 which is normally closed by the plate 23a. The draft of air in the feed passage does not draw the heavier particles between the spokes 23b, 5 but such particles are allowed to fall into the receptacle 22 past the lateral sides of the member 16.

Thus substantially all of the heavier particles of foreign matter, including the gravel which is 10 apt to damage the grinding plates, is prevented from reaching the grinding surfaces. It will be now evident that the conical projection 16 serves the purposes of properly distributing the material in the feed passage, of directing the foreign 15 matter into the trap receptacle 22 and of affording a support for the bearing 15 located close to the grinding head 13.

The annular shoulders or rings 16a are particularly useful in effecting a force feed of 20 roughage, such as pieces of corn cob, which have a tendency to work back and escape from the feed draft carrying the finer or lighter particles.

Having described my invention what I claim 25 as new and desire to protect by Letters Patent is:

1. In a grinding mill, a shaft, a grinding head mounted on said shaft and having a feed opening therethrough, means for supplying the material to be ground, a feed conduit connecting said supply means with said opening, a substantially 30 conical member projecting into said conduit around said shaft to direct said material toward said opening and a receptacle disposed adjacent to the base of said member to collect the heavier foreign matter.

2. In a grinding mill, a horizontal shaft, a grinding head mounted on said shaft and having a feed opening therethrough, a hopper for material to be ground mounted above said shaft, a feed conduit connecting said hopper with said 40 opening, a substantially conical member projecting into said conduit beneath said hopper and extending around said shaft to direct said material toward said opening and a receptacle disposed beneath said member to collect the heavier foreign matter.

3. In a grinding mill, a substantially horizontal shaft, a grinding head mounted on said shaft and having spokes between which material to be ground is fed, a hopper for said material mounted 50 above said shaft, a feed conduit connecting said hopper with said head, a substantially conical deflector extending transversely in said conduit and around said shaft toward said head to distribute said material between said spokes, a substantially annular portion of said conduit being provided around said deflector adjacent to said head and said deflector having a bearing chamber therein and a bearing for supporting said shaft adjacent to said head mounted in said chamber.

4. In an attrition mill, a shaft, a grinding head mounted on said shaft and having a feed opening therethrough, grinding means associated with said head, means for supplying material to be ground, a feed conduit connecting said supply 60 means with said opening, a substantially conical member projecting transversely in said conduit and extending around said shaft to direct said material toward said opening, said grinding means and head being arranged to create a swirling draft of air in said conduit and around said member to draw the lighter particles of material into said opening and a receptacle disposed adj-

acent to the base of said member to collect the heavier particles of foreign matter separated from said material.

5. In an attrition mill, a horizontal shaft, a grinding head mounted on said shaft and having a feed opening therethrough, grinding means associated with said head, means above said shaft for supplying material to be ground, a feed conduit connecting said supply means with said opening, a substantially conical member projecting transversely in said conduit directly beneath said supply means and extending around said shaft to direct said material toward said opening, said grinding means and head being arranged to create a swirling draft of air in said conduit and around said member to draw the lighter particles of material into said opening and a receptacle disposed beneath said member to collect the heavier particles of foreign matter in said material.

6. In an attrition mill, a shaft, a grinding head mounted on said shaft and having a feed opening therethrough, grinding means associated with said head, means for supplying material to be ground, a feed conduit connecting said supply means with said opening, a substantially conical member projecting transversely in said conduit and extending around said shaft to direct said material toward said opening, said grinding means and head being arranged to create a swirling draft of air in said conduit and around said member to draw the lighter particles of material into said opening, a bearing supported by said member adjacent to said head and a receptacle disposed adjacent to the base of said member to collect the heavier particles of foreign matter separated from said material.

7. In a grinding mill, a shaft, a grinding head mounted on said shaft and having a feed opening therethrough, a feed conduit communicating with said opening, a substantially conical member projecting into said conduit to direct material to be ground toward said head and substantially annular projections on said member to direct said material around said member.

8. A mill of the character described comprising a horizontal rotary shaft, grinding means mounted thereon, an inclined feeder shoe proper and an enclosing conical shell therefor extending substantially parallel with the feeder shoe, both 50 having their lower ends conical laterally and enclosing said shaft and having said ends disposed directly adjacent to said grinding means, and a bearing for said shaft located within the conical end of the shoe proper and adjacent to said grinding means, substantially as described.

9. A mill of the character described comprising a casing, a horizontal rotary shaft mounted therein, a grinding disc having feed openings therein and mounted on the end of said shaft in 60 said casing, a laterally conical feeder shoe disposed directly adjacent to said grinding disc and consisting of a shoe proper and an enclosing conical shell therefor extending substantially parallel with the feeder shoe forming a circular conical feed passage enclosing said shaft and leading to said openings, the body of said shoe proper having near said grinding disc a hollowed out opening and cover therefor, and a bearing for said shaft located in said body opening near the grinding 70 disc, substantially as described.

DIX B. McLAUGHLIN.
